UNITED STATES PATENT OFFICE.

MARKUS WALINT, OF BERWICK, PENNSYLVANIA, ASSIGNOR OF ONE-THIRD TO ALBERT GREENBERGER AND ONE-THIRD TO LOUIS MARKO, BOTH OF BERWICK, PENNSYLVANIA.

ICE-MAKING DEVICE.

1,044,310.

Specification of Letters Patent. Patented Nov. 12, 1912.

Application filed April 18, 1912. Serial No. 691,689.

To all whom it may concern:

Be it known that I, MARKUS WALINT, a subject of the Emperor of Austria-Hungary, and a resident of Berwick, in the county of Columbia and State of Pennsylvania, have made certain new and useful Improvements in Ice-Making Devices, of which the following is a specification.

My invention relates to improvements in devices for making artificial ice, and it consists in the combinations, constructions and arrangements herein described and claimed.

An object of my invention is to provide means whereby a number of blocks of ice may be quickly and cheaply manufactured through the agency of a freezing compound.

A further object of my invention is to provide a machine or device for manufacturing ice which will accomplish the freezing of the water in a very short time.

Other objects and advantages will appear in the following specification, and the novel features of the device will be particularly pointed out in the appended claim.

My invention is illustrated in the accompanying drawings forming part of this application in which similar reference characters indicate like parts in the several views, and in which—

Figure 1 is a vertical section through the device, Fig. 2 is a plan view of the device with the cover removed, Fig. 3 is a section along the line 3—3 of Fig. 1, and Fig. 4 is a section along the line 4—4 of Fig. 1.

In carrying out my invention I provide a rectangular casing 1 provided with a partition 2 which divides the casing into two compartments 3 and 4 respectively. The compartment 3 is the ice making compartment, while the compartment 4 is designed to house the motor and fan.

The casing 1 is made of wood or other similar nonconducting materials. The compartment 3 is lined with tin or other suitable metal such as shown at 5, and the space between the metal lining 5 and the outer casing is filled with some non-conductor 7, such as mineral wool. The casing is provided with a hinged cover 8, as shown in Fig. 4.

Disposed within the compartment 4 is a motor M and a fan F, the motor being connected with the fan so as to drive the latter. Within the compartment 3 is a coil of pipe

which lies above the floor of the compartment. This coil of pipe in fact, consists of two pipes, one within the other as shown in Fig. 4. The outer pipe 9 communicates with a water supply 10 while the inner pipe 9^x communicates with the fan F. The opposite end of the pipe 9 has an outlet 11 while the pipe 9^x is bent inwardly toward the center of the compartment and terminates in a funnel or bell 9^y. Disposed on the inner lining 5 near the top on each side of the compartment 3 is an elongated flange 12 as shown in Figs. 2 and 4.

Arranged to fit within the compartment 3 are a series of cans 13 and 14. These cans are provided with hooks 15 which arrange to engage the flange 12 so as to suspend the cans within the compartment. The cans 13, which alternate with the cans 14, are designed to receive a freezing mixture. This freezing mixture may be any suitable substance, but is preferably a mixture of ice, salt and lye, the latter consisting almost entirely of potash. The salt may be coarse salt and does not have to be pure, since any volatile matter, which would tend to render the air surrounding the cans impure, will be carried away in the manner hereinafter explained.

From the foregoing description of the various parts of the device the operation thereof may be readily understood. The stop cock 10^a in the water inlet 10 is opened, the cock 11^a of the outlet 11 also being opened. This permits water to flow into the pipe 9. As soon as the pipe is filled the cocks 10^a and 11^a are closed. The cans containing the freezing mixture are placed on their supports and those containing the water to be frozen are placed between the cans containing the freezing mixture as described.

The cover 8 is closed and the fan is started by the motor. Air is drawn in through the opening 15 (see Fig. 3) into the compartment 4 and into the fan F, whence it is forced into the pipe 9^x which is surrounded by water. Here the air is given a preliminary cooling. The air is delivered from the funnel 9^y underneath the cans 13 and 14. It will be noted that there is a space surrounding the cans by which the air can have access to all sides of the can. The fan rotates slowly and there is a slow current of air which passes up around the cans

and is discharged through the opening 17 (see Fig. 1) into the outer compartment. An opening 18 is provided in the casing so as to permit the slow discharge of air. The 5 passage of the air through the pipe 9 causes the air to become chilled before being passed over the cans. The water remains chilled owing to its proximity to the cans. It has been found that with a slight current 10 of air flowing around the cans the time of freezing the ice is much less than where no such circulation takes place. Furthermore, the air is prevented from becoming foul by the steady, but small discharge through the 15 opening 18. When the air is given a preliminary chilling prior to its delivery into the space around the cans all of the cans containing the ice produce about the same product, but where the air is not chilled 20 there is a tendency for the can which is situated nearest the discharge pipe to take a longer time in freezing a block of ice. After the ice has been frozen the cans may be lifted out of the compartment and emptied 25 of their contents. It is found in practice

that one charge of freezing mixture is sufficient for three or four batches of ice.

I claim:

In a device for making artificial ice, a casing divided into two compartments, a 30 fan in one compartment, a motor therefor, the other compartment being provided with non-conducting walls, a coil of concentric pipes disposed near the bottom of the latter compartment, a connection between the fan 35 and the inner of said pipes, the outer of said pipes being connected with a water supply, a series of cans disposed within said compartment above said pipes, said cans being spaced from the walls of the compartment, one end of said air pipe terminating below the bottom of said cans, a pipe establishing communication between said compartments, and an air passage leading from one of said compartments to the outer atmosphere.

MARKUS WALINT.
